E. A. CLARK,
GAS BURNER FOR WELL DRILLING FORGES,
APPLICATION FILED MAR. 24, 1921.
1,406,346. Patented Feb. 14, 1922.

UNITED STATES PATENT OFFICE.

EARLE A. CLARK, OF TULSA, OKLAHOMA.

GAS BURNER FOR WELL-DRILLING FORGES.

1,406,346.

Specification of Letters Patent. Patented Feb. 14, 1922.

Application filed March 24, 1921. Serial No. 455,253.

To all whom it may concern:

Be it known that I, EARLE A. CLARK, a citizen of the United States, residing at Tulsa, in the county of Tulsa and State of 5 Oklahoma, have invented certain new and useful Improvements in Gas Burners for Well-Drilling Forges; and I do hereby declare the following to be a full, clear, and exact description of the invention, such as 10 will enable others skilled in the art to which it appertains to make and use the same.

My invention relates to improvements in gas burners for well drilling forges, and its object is to produce a burner in which the 15 air and gas will be completely mixed before passing out of the burner structure to the point of ignition.

Heretofore in the construction of most of the burners of this kind, it has been necessary to have them enter the forge from the front, and as a result, the gas connection was knocked off, or injured by the workmen with the heavy bits to be heated.

This danger is eliminated in the case of 25 the present burner, which enters the forge at the side.

Another object which I have in view, is to produce a burner capable of generating a higher degree of heat, than those formerly 30 in use.

With the foregoing objects outlined and with other objects in view, the invention consists in the novel features hereinafter described in detail, illustrated in the accompanying drawing, and more particularly pointed out in the appended claims.

In the accompanying drawings;

Fig. 1 illustrates a front view of a forge, showing the burner in dotted lines.

40 Fig. 2 is a view taken on line 2—2 of Fig. 1 and shows a cross section of the burner.

Fig. 3 is a view taken on line 3—3 of Fig. 1 and showing an end view of the burner, and

45 Fig. 4 is an enlarged cross sectional view of a portion of Fig. 2 showing the oblique walls of the perforations of the air conducting pipe.

In the drawings, 1 represents the outer 50 pipe of the burner, and is provided with a branch or gas inlet pipe 4, and connected to any desired type of blower at 8. Within the pipe 1 is an air or mixing conduit 2, which is provided with perforations 6 pref- 55 erably arranged spirally around its circum-

ference. These perforations, as shown in Fig. 4, are preferably formed with oblique walls, to facilitate the suction of the gas into the mixing conduit.

At each of its ends, the conduit 2 expands 60 and is connected to the outer pipe 1 as at X, forming a space or closed chamber 5, between the two pipes into which the gas inlet pipe 4 opens.

The extension 7 is preferably arranged at 65 right angles to the pipes 1 and 2, and serves to conduct the mixture of gas and air to the point of ignition 9 in the base of the forge entering the same at one side thereof. 10 represents the top portion of the forge, and 70 is adapted to receive the drilling tools for heating purposes.

The operation of the device is apparent. A blast of air is introduced through pipe 2, entering at the point 3, the pressure being 75 generated by a steam or other blower (not shown). At the same time, gas is admitted through the inlet pipe 4, to the chamber 5, and by means of the spirally arranged obliquely disposed perforations 6, acted upon 80 by the current of air, is drawn in and mixed with the air in the pipe 2, and passes into the extension 7 of the burner, which is inserted in the base of the forge, at one side thereof. 85

It is obvious that the greater the force of the air as it passes through the pipe 2, the more gas will be drawn into said pipe, and the hotter the flame in the forge will be.

In practice, I have found that the form of 90 my invention, illustrated in the drawing and referred to in the above description, is most efficient and practical, but I desire to emphasize the fact that various minor changes in the details of construction, and 95 arrangement of parts may be made when required, without sacrificing any of the advantages of my invention as set forth.

What I claim and desire to secure by Letters Patent is:—

1. A gas burner comprising an outer pipe, bent at right angles at one end, and provided with a gas connection, an inner pipe having its ends expanded and attached to said outer pipe, forming a chamber between the two, 105 said inner pipe being provided with spirally arranged openings, and means for forcing a blast of air through the central pipe, whereby the gas and air may be mixed thoroughly and led to the point of combustion. 110

2. The combination with a forge, of a burner comprising an outer pipe provided with a gas inlet at one end, and an extension leading into the forge at the other, an inner pipe having its ends expanded and attached to said outer pipe, forming a closed chamber, said inner pipe being provided

with spirally arranged openings and means for forcing a blast of air through the inner pipe, whereby the gas and air may be mixed thoroughly in the inner pipe and conducted to the forge. 10

In testimony whereof I affix my signature.

EARLE A. CLARK.
